MANHOLE CONSTRUCTION

Arthur P. Kramer, Los Angeles, Calif., assignor, by direct and mesne assignments, of one-fourth to Nick Satara, one-fourth to Martin Maganovich, both of Los Angeles, Calif., and one-fourth to Mazella H. Gillespie

Application May 2, 1932, Serial No. 608,634

12 Claims. (Cl. 94—35)

My invention relates generally to sewers, storm drains and the like, and more particularly to manhole covers therefor.

An object of my invention is the provision of a novel manhole cover which is structurally characterized by simple, efficient, inexpensive, but substantial means enabling the closure lid of the cover to be securely locked rigidly to the frame of the cover against accidental displacement or vibration by traffic or other objects moving thereover, yet permitting the lid to be readily released and removed from the frame as the occasion may require.

Another object of my invention is the provision of a novel manhole cover wherein the lid is locked to and released from the frame by rotational movement of the lid effected by the use of a suitable prying tool, and wherein novel means is provided for dislodging particles of dirt and other foreign substances which may collect in the frame of the manhole, and discharge such foreign substances into the interior of the cavity closed by the manhole lid, so as to enable the lid to be freely turned when desired and thereby facilitate its release from, and securement to, the frame. Another object is to provide novel and simple means whereby a closure lid may be securely locked in a manhole frame against accidental displacement and rattling due to street traffic; and which may be easily and quickly removed therefrom regardless of foreign substances that may have entered the parts while in place or use.

The invention resides in the parts and combination of parts more particularly hereinafter described and pointed out in the appended claims.

Other objects, advantages and features of my invention may appear from the accompanying drawing, the subjoined detail, description and the appended claims.

The accompanying drawing illustrates the invention in a form I at present deem preferable.

Figure 1 is a top plan view of a manhole cover embodying my invention.

Fig. 2 is a vertical axial sectional view taken on line 2—2, Fig. 1.

Fig. 3 is a horizontal sectional view taken on line 3—3, Fig. 2 and looking in the direction of the arrows.

Fig. 4 is a top plan view of the manhole frame with the lid removed therefrom.

Fig. 5 is a vertical axial sectional view taken on line 5—5, Fig. 4.

Fig. 6 is a bottom plan view of the lid.

Fig. 7 is a side elevational view of the lid.

Figs. 8 and 9 are diagrammatic views showing the interlocking parts of the manhole cover and the manner in which a prying tool is employed to lock and release the lid from the frame of the manhole cover.

My invention comprises a manhole frame 1 and a lid 2, the frame having an annular base flange 3 from which rises an annular rim 4. The inner periphery of the base flange 3 defines the manhole opening 5 and is bounded by an annular seat 6 preferably supporting an annular packing ring or gasket 7 concentrically with respect to the rim 4.

Projecting from the inner periphery of the rim 4 are cam members 8 of which in the present instance there are three in number equally spaced apart circumferentially and which have their bottom radial surfaces extending obliquely or spirally in an upward direction with respect to the axis of the frame so as to provide cams 9. The cam members are notched radially to define series of lugs or teeth with intervening recesses 10 in any of which a suitable prying tool 11 is adapted to be extended in a manner and for a purpose to be later fully described. The bottom surfaces of these recesses 10 incline downwardly and radially inward as indicated at 12 to permit dirt and other foreign substances entering the openings to discharge therefrom into the manhole with which the cover is associated.

The closure lid 2 comprises a top plate 13 suitably reenforced to safely support traffic loads, and provided with air vents 14 and a plurality of peripheral recesses 15 for insertion of a prying tool 11 into the series of recesses 10 of the cam members 8 in a manner to be later described. The top plate 13 is of a diameter to be freely received within the rim 4 of the frame 1, and depending from the top plate is an annular rim or skirt 16, the outside diameter of which permits the rim to pass within the cam members 8 and the lower extremity of which is adapted to seat upon the seat provided therefor in the manhole frame 1. It will thus be seen that the lid 2 has a rim 16 adapted to be received within the rim 4 of the frame in spaced relation thereto to define an annular space b between the rims 4 and 16 and into which space b the spaced apart and circumferentially extending cam members 8 project. Projecting from the outer periphery of the rim 16 and into the annular space b are cam members 17 of which there are three in number equally spaced circumferentially and having their top radial surfaces extending obliquely or spirally

in a downward direction with respect to the axis of the frame 1 to provide cams 18 complementary to the cams 9 of the cam members 8 for co-action therewith in forcing the lid axially in the frame 5 as the lid is rotated in one direction, and at the same time providing an interlock between the lid and frame when the co-acting cam surfaces 9 and 18 have been brought into engagement with each other.

10 One end of each of the cam members 17 is beveled so as to be tangentially disposed with respect to a circle described within the rim of the lid, to thereby provide scrapers 19 operable upon rotation of the lid in one direction, to scrape 15 any accumulation of dirt from the inner periphery of the frame rim 4, in advance of the scrapers when the lid is being moved to releasable position and thereby aid in easy rotation of the lid from cam engaging or locking position. The scrapers 19 are so positioned and arranged as to 20 direct the removed dirt through passages 20 in the rim 16 of the lid 2 and into the interior of the cavity closed by the manhole lid. The rim 16 is provided with other passages 21 disposed directly below the pry bar or prying tool receiving openings 15, and through which said other 25 passages 21, dirt that may be dislodged by the pry bar 11 from the recesses 10 of the cam members 8 when the pry bar 11 is inserted in said recesses 10 through the openings 15, may be discharged into the manhole.

30 In the operation of my invention, let it be assumed that the frame 1 is embedded in a street or roadway so that the top edge of its rim 4 is flush with the street surface, and that the lid 2 is to be applied to the frame to close the manhole.

35 The lid is first placed in the frame in a position circumferentially relative to the frame, for its cam members 17 to pass between the adjacent cam members 8 of the frame. The lower extremity of rim 16 of the lid will now be resting upon the seat provided therefor in the manhole frame 1, with the cams 18 of the members 17 being so disposed vertically with respect to the 40 cams 9 of the members 8, that upon rotation of the lid by the prying tool 11 as hereinafter described, in a counterclockwise direction as viewed in Fig. 1, the cams 9 and 18 will be brought into engagement or contact with each other and thereby co-act in forcing the lid axially and 45 downward against its seat, such as the gasket 1 so as to place the latter under compression and thereby seal the joint between the lid and frame.

50 In order to enable the lid to be readily rotated with but negligible manual effort, the pry bar 11 illustrated in Figs. 8 and 9, is inserted in the recess 10 of the series of recesses 10 which happens to register with one of the recesses 15 in the top plate 13 of the lid 2 as shown in Fig. 8. The pry bar 11 is now rocked as a lever in the 55 direction indicated by the arrow *a* in Fig. 9, to rotate the lid in the frame 1 to bring the cams 9 and 18 into engagement and to cause the cams 9 and 18 to function in advancing the lid axially downward as above described.

60 It will be apparent that a tremendous leverage is applied to rotate the lid 2 in its frame 1, and is obtained with the pry bar due to the correlation of the recesses 15 and recesses 10, as the fulcrum point of the pry bar in one of said recesses 10 is in close proximity to the point of application of the load imposed on the bar by the 65 resistance of the lid to turning, all with respect to the long lever arm provided between the point of application of the load and the free end of 70 75

the bar to which the force is applied, and the fact that the recesses 10 and openings or notches 15 are at the periphery of the lid 2 that is being rotated.

It is to be understood that the recesses 15 of 5 the lid are so spaced circumferentially to each other and to the series of recesses 10 of the cam members 8, that the recesses 10 of each series will successively register with a different one of the recesses 15 as the lid is rotated, in other words a recess 10 is always brought into register with an opening 15 to permit the pry tool 11 to be operatively inserted in a recess 10. The pry bar is successively inserted in the recess 15 a recess 10 with which it registers, and is manipulated as a lever to rotate the lid in its frame, this operation being repeated until the annular rim 16 of the lid is seated with sufficient tightness against its seat due to the cam action of the cam members 8 and 17 to lock the lid in its frame. 10 In the fully seated position of the lid, its top surface will be flush with the street surface, and the cam members 8 and 17 of the frame and lid respectively, will co-act in forming an interlock to rigidly secure the lid to the frame against 15 accidental displacement by traffic loads and prevent vibration or rattling of the lid in the frame, yet will permit the lid to be readily released from the frame by a reversal of the above described 20 operation of the pry bar as a lever.

30 In turning the lid in a clockwise direction to release the lid from the frame, any foreign substances such as dirt and dust which may have accumulated on the inner periphery of the frame rim 4 in advance of the cam members 17 will be 35 effectively scraped therefrom by the scrapers 19, and such foreign substances will be directed through the passages 20 so as to discharge the same into the manhole, thus facilitating the 40 removal of the lid.

45 Furthermore, should any dirt have accumulated in the recesses 10 and recesses 15, it will be automatically cleared therefrom and discharged into the passages 21 and into the manhole upon the insertion of the pry bar 11 therein, as the pry bar will force such dirt through the recesses 15 and recesses 10 and along the inclined bottoms 12 of the recesses 10 and thence through the passage 21 correlated with the particular recess 15 being utilized.

50 It will thus be manifest that such accumulations of dirt as would otherwise hamper and possibly prevent the removal of the lid, will be effectively disposed of and the otherwise secure lock obtained by the co-action of the cam surfaces 9 and 18 may be easily broken by application and 55 operation of the pry tool 11, so that the lid may be instantly released without any appreciable manual effort.

60 What I desire to claim and secure by Letters 60 Patent is:—

65 1. In a manhole cover construction, the combination of an annular fixed manhole frame formed upon its inner circumference with a plurality of spaced apart outwardly projecting cams, the lower edges of which are beveled longitudinally and the upper edges of which are straight, said cams being serrated to provide a series of notches transversely thereof; and a manhole cover having an annular extension depending into the 70 opening in the manhole frame; a plurality of spaced apart outwardly projecting cams on the outer circumference of said extension and the upper edges of which are beveled longitudinally and adapted when in position to engage the 75

- beveled under surface of the frame cams; said cover being formed with notches adapted to successively expose therethrough the notches in the frame cams to thereby permit a prying tool 5 to be inserted into said notches to tighten and loosen the cover in the frame.
2. A manhole cover comprising a frame having an annular rim and seat; a lid having a rim adapted to be received within the rim of the frame in spaced relation thereto to define an annular space between the rims; spaced apart and circumferentially extending cam members projecting from the rims of the frame and lid into said annular space and co-acting in response 10 to rotation of the lid in one direction, to advance the lid axially against said seat; the rim of the lid having passages therethrough at one end of the respective cam members; the said one end of each of the cam members of the lid being 15 provided with scraping edges adapted to engage the inner periphery of the frame rim to scrape foreign substances from the latter and to direct such substances through the openings of the lid rim during rotation of the lid in one direction.
- 20 3. A manhole cover comprising a frame having an annular rim and seat; a lid having a rim adapted to be received within the rim of the frame in spaced relation thereto to define an annular space between the rims; spaced apart and circumferentially extending cam members projecting from the rims of the frame and lid into said annular space and co-acting in response to rotation of the lid in one direction, to advance the lid axially against said seat; the rim of the lid 25 having passages therethrough at one end of the respective cam members; and means on the lid adapted to engage the inner periphery of the frame rim so as to effect scraping of foreign substances therefrom and to direct such removed 30 substances through said passages as the lid is rotated in one direction, whereby to clean such surfaces of the frame to facilitate removal of the lid.
- 35 4. A manhole cover comprising a frame having an annular rim and a seat; a lid adapted to be received within the rim of the frame; means on the frame and lid co-acting in response to rotation of the lid in one direction, to advance the lid axially against said seat; and means correlated 40 with the lid for scraping foreign substances from the inner periphery of the frame rim as the lid is rotated in one direction.
- 45 5. A manhole cover comprising a frame having an annular rim and a seat; a lid adapted to be received within the rim of the frame; means on the frame and lid co-acting in response to rotation of the lid in one direction, to advance the lid axially against said seat; and means correlated 50 with the lid for scraping foreign substances from the inner periphery of the frame rim as the lid is rotated in one direction.
- 55 6. A manhole cover comprising a frame having an annular rim and a seat; circumferentially spaced apart cam members projecting from the inner periphery of said rim; a lid adapted to be received within said rim and having a depending skirt and circumferentially 60 spaced apart cam members on said skirt with which the cam members of the frame are adapted to co-act to force said skirt against said seat as the lid is rotated in one direction; the lid having a plurality of circumferentially spaced openings 65 through which a prying tool is adapted to be inserted; the cam members on said frame each having a series of recesses into which the prying tool is adapted to be extended from said openings in the lid; said recesses being so related circumferentially to each other and to the openings in the lid, that said recesses will successively register with a different one of the lid openings as the lid is rotated, whereby to enable the pry- 70 75
- ing a plurality of circumferentially spaced openings through which a prying tool is adapted to be inserted; the cam members of the frame each having a series of recesses into which the prying tool is adapted to be extended from said openings in the lid; the recesses of said series being so related circumferentially to each other and to the said openings in the lid, that the recesses of said series will successively register with a different one of the lid openings as the lid is rotated, whereby to enable the prying tool to be successively inserted in the lid openings and manipulated as a lever to effect rotation of the lid in one direction or the other.
7. A manhole cover comprising a frame having circumferentially spaced cam members; a lid having circumferentially spaced cam members co-acting with the cam members of the frame to feed the lid axially when rotated relative to the frame; the lid having a plurality of circumferentially spaced openings through which a prying tool is adapted to be inserted; the cam members of the frame each having a series of recesses into which the prying tool is adapted to be extended from said openings in the lid; the recesses of said series being so related circumferentially to each other and to the openings in the lid, that the recesses of said series will successively register with a different one of the lid openings as the lid is rotated, whereby to enable the prying tool to be successively inserted in the lid openings and manipulated as a lever to effect rotation of the lid in one direction or the other.
8. A manhole cover comprising a frame; a lid; means on the frame and lid for feeding the latter axially when rotated in the frame; the lid having a plurality of circumferentially spaced openings into which a prying tool is adapted to be inserted; the frame having a circumferential series of recesses so related circumferentially to the openings in the lid as to successively register with a different one of the lid openings as the lid is rotated, whereby to enable the prying tool to be successively inserted in the lid openings and manipulated as a lever to effect rotation of the lid in one direction or the other.
9. A manhole cover comprising a frame; a lid; means on the frame and lid for feeding the latter axially when rotated in the frame; and co-acting means on the frame and lid with which a prying tool is adapted to co-act in rotating the lid by successive insertions and manipulations of the prying tool as a lever at different locations circumferentially on the lid.
10. A manhole cover comprising a frame having an annular rim and an annular seat; circumferentially spaced apart cam members projecting from the periphery of said rim; a lid adapted to be received within said rim and having a depending skirt and circumferentially spaced apart cam members on said skirt with which the cam members of the frame are adapted to co-act to force said skirt against said seat as the lid is rotated in one direction; the lid having a plurality of circumferentially spaced openings through which a prying tool is adapted to be inserted; the cam members on said frame each having a series of recesses into which the prying tool is adapted to be extended from said openings in the lid; said recesses being so related circumferentially to each other and to the openings in the lid, that said recesses will successively register with a different one of the lid openings as the lid is rotated, whereby to enable the pry-

ing tool to be successively inserted in the lid openings and manipulated as a lever to effect rotation of the lid in one direction or the other; said recesses in the cam members of the frame 5 having their lower portions inclining downwardly and radially inward; the rim of the lid having passages disposed directly below the openings in the lid and adapted to receive foreign substances forced from the recesses of the cam members of the frame upon insertion of the prying tool in 10 said recesses.

11. A manhole cover comprising a hollow frame having a circumferential series of recesses for receiving a prying instrument; an annular seat 15 on said frame; a lid adapted to be received in the frame and having an opening adapted to successively register with the frame recesses as the lid is rotated; a skirt depending from said lid and adapted to seat on said seat; and co-acting means 20 on the frame and skirt for advancing the lid axially to seat said skirt on said seat and for lock-

ing the lid in the frame in response to rotation of the lid by manipulation of the pry bar as a lever when inserted in the recesses of the frame and lid.

12. A manhole cover comprising a hollow frame having a circumferential series of recesses for receiving a prying instrument; a lid adapted to be received in the frame and having an opening 5 adapted to successively register with the frame recesses as the lid is rotated; and co-acting means 10 on the frame and lid for advancing the lid axially and locking the lid in the frame in response to rotation of the lid by manipulation of the pry bar as a lever when inserted in the recesses of the frame and the opening in the lid; the lid having 15 passages through which foreign substances forced by the pry bar from the said recesses upon the insertion of the pry bar into said recesses is adapted to be discharged into the manhole with 20 which the cover is associated.

ARTHUR P. KRAMER.
